LUBRICATING DEVICE FOR INTERNAL-COMBUSTION ENGINES.

Application filed September 1, 1921. Serial No. 497,589.

This invention relates to lubricating devices for internal combustion engines, and a particular object thereof is to provide a device preventing the thinning of the lubricating oil by the addition of lighter hydrocarbons utilized as fuel for the engine. With the ordinary gasoline engine or engine of similar character utilizing the lighter hydrocarbons as a fuel more or less of the fuel charge depending upon the tightness of the piston rings, finds its way into the lubricating oil in the crank case of the engine reducing its lubricating quality. This invention seeks to provide means to remedy such defect and to not only prevent passage of the portions of fuel charge between the piston and cylinder wall into the crank case but also to remove such waste fuel charge from between the piston and cylinder wall and reclaim the same. The volatile constituents are separated from the heavier lubricating oil removed therewith and are discharged to the intake manifold of the engine and the refined lubricating oil is returned to the crank case for subsequent use. Various novel features of the invention, such for instance as the means of supplying the piston with a cooled lubricating oil, and a particular means in the structure of the piston whereby the lubricating oil plus whatever volatile oils become mixed therewith may be removed from between the piston and cylinder walls and mechanism by means of which the piston may be intermittently provided with a fresh lubricating oil, are hereinafter more fully described and claimed. These and various other features of the invention in the preferred form of construction thereof are shown in the accompanying drawings in which—

Fig. 1 is an elevation showing my improved lubricating oil refining device in its general relationship with an internal combustion engine.

Fig. 2 is a vertical longitudinal section of the oil refining structure.

Fig. 3 is a side elevation thereof.

Fig. 4 is a plan view partly in section showing the oil filter and valve controlling the flow of oil thereinto.

Fig. 5 is a similar view partly in section showing the valve structure for controlling the flow of exhaust gases into the refining device.

Fig. 6 is a detail in section of an oil dis-

tributor for delivering oil at intervals to between the piston and cylinder wall.

Fig. 7 is a side elevation of the piston showing the oil groove.

Fig. 8 is a side elevation of a multiple cylinder engine embodying the invention.

The oil refining device is shown more particularly in Figs. 2 to 5 and preferably is adapted to be mounted in any convenient place, for instance on the engine side of the cowl of an automobile, by means of a bracket 1 extending about the body of the refiner device and having the outturned ends 2 adapted for attachment to the cowl. The body of the oil refining device consists of a central casting 3 on the lower end of which may be attached a thin walled cup shaped member 4 providing an oil chamber. On the upper end of the casting 3 is attached a similar outer casing 5 and an inner casing 6 spaced therefrom and providing a chamber 7 into which the exhaust gases may pass through the inlet 8 which may be connected with the exhaust manifold of the engine by a conduit 9 as shown in Fig. 1. Within this casing 6 is an open ended shell 8 which may be secured to the central casting 3 by a nut on the central stem 10. The stem 10 is threaded into the upper side of the casting 3 and the nut forces the casing 8 tightly in contact with the packing 11 between the bottom of the shell 8 and the casting 3. This shell 8 has an aperture 12 therein registering with an aperture 13 in the upper part of the casting 3 as shown in Fig. 2. The walls of the casing 8 are outwardly flared as shown in the said figure, and spaced from the wall of the case 6 to provide a cylindrical chamber 14 between the substantially concentric walls of the casings 6 and 8 which is narrower at the upper end than at the bottom. The shell 8 is less in length than the shell 6 and oil that passes into the chamber 14 as hereinafter stated, may overflow from the chamber 14 into the interior of the shell 8 and eventually, as hereinafter described, find its way through the aperture 13 in the casting 3 into the oil chamber formed by the casing 4.

Oil to be refined passes into the chamber 14 through a screen 15 shown in Figs. 3 and 4 which is preferably tubular in form and supported in a cylindrical chamber 16 formed in the side of the casting 3 as will be understood from Figs. 3 and 4. In Fig. 3 it will

be seen that oil passing into the interior of the screen 15 may pass out through the side thereof and through an aperture 17 and upward into the refining chamber 14. This screen is held in place by a cap 18 as shown in Fig. 4 which engaged against the end of the screen member for holding it in position and also provides a closure for the chamber 16 at said end.

10 Oil is led into the screen 15 through an inlet conduit 19 to which a conduit 20 from the source of supply is to be connected for instance as shown in Fig. 1. A valve 21 is provided in the conduit 19, which valve has 15 a longitudinal bore as shown by dotted lines in Fig. 4 which opens, by means of the aperture 22 through the side of the valve, into the chamber 23 in which the valve 21 is positioned. The valve is of the cone type having a pointed end 24 held away from its seat 25 by a coiled spring 26. The valve shown in Fig. 4 is in normal position and oil may flow freely through the valve and the conduit 27 into the end of the screen member 28 and through the screen member and aperture 17 in the casting 3 into the chamber 14. As hereinafter more fully described the oil is caused to flow through these conduits by reduction of pressure on the intake manifold 20 of the engine and to prevent an excessive oil flow is the reason for the provision of this valve member 21. On low speeds of the engine or whenever an excessive vacuum is produced in the intake manifold, the valve 21 will be drawn toward its seat restricting, to a greater or less extent depending upon the extent of reduction of pressure in the intake manifold, the flow of oil through the refiner and prevents an extreme exhaust 30 pressure being applied to the space between the piston and cylinder of the engine which, as hereinafter shown, provides the source of supply for the line 20.

I have so arranged the refiner device that 45 it is automatic and intermittent in operation—that is, that the operation for a time draws the oil from the supply line 20 by a vacuum produced in the interior of the shells 6 and 8 by means of the reduction of pressure in the intake manifold of the engine and this oil is discharged into the casing 4 upon the level of the oil therein falling below a predetermined point at which time the interior of the shell 8 is emptied of its 55 contents raising a float in the casing 4 which closes the aperture 12. The closing of the aperture 12 again submits the chamber 14 to the reduced pressure of the intake manifold. The mechanism for this purpose is 60 shown more particularly in Fig. 2. The upper end of the stem 10 is hollow for a distance and by means of a channel 28 is open to the top of the chamber 14 and interior of the shell 8. It is to be noted that I have 65 provided a cap 29 that is cup like in form

at the upper end of the member 6 extending downwardly for a short distance into the open end of the shell 8. This is in the nature of a baffle to direct oil flowing upward in the chamber 14 over and downward into the shell 8 and prevents the oil being passed in close proximity to the suction channel 28. The opening for the conduit 28 is in the recess provided in the upper end of the casting 6 and this recess is open to the chamber 14 and interior of the casing 8 by means of an aperture 30 in the said member 29. The conduit 28 is in communication with the intake manifold of the engine by means of a pipe line 31 as shown in Fig. 1, the intake 70 manifold being indicated at 33.

In order for partial vacuum to be produced in the interior of the shell 8 and in the chamber 14, the said chamber and shell must be closed to atmosphere and in order for the oil accumulating in the shell 8 to flow therefrom through the apertures 12 and 13 into the casing 4 the pressure in the upper end of the chamber 14 and in the casing 4 must be equalized. This is accomplished by the mechanism shown particularly in Fig. 2 which consists of a float 33 pivotally supported on the bar 34 which in turn is pivoted to a bracket 35 provided on the casting 3. To this bar 34 is pivotally secured a link 36 which at the opposite end is pivotally secured to a lever 37. The lever 37 is pivoted to a depending lug 38 supported in the casting 3. There is also another lever 39 pivoted to the lug 38 and the ends of these two levers are connected together by a coiled spring 40. This spring, in the position shown in the part Fig. 2, tends to hold the levers with the ends below the pivot point. The end of the lever 39 is connected with the stem of a valve 41 which is adapted to seat against the aperture 42 in the casting 3, which aperture is open to atmosphere by means of a channel or conduit 43. When the lever 39 and valve 41 are in the position shown the aperture 42 is closed to atmosphere. Opening the valve opens the chamber in the casing 4 to atmosphere and this would permit oil to flow out of the chamber 4 through the outlet channel 44 in the bottom thereof. On this lever 39 is a second valve 45 that controls the lower end of a tube 46 supported in the casting 3 and extending upward and terminating well above any possible oil level in the casing 8, and it is to be noted that, when the valve 41 is closed, thereby closing the case 4 to atmosphere, the chamber in the casing 8 is also open to the chamber 4 through the tube 46, permitting oil to flow from the casing 8 into the chamber 4 through the apertures 12 and 13. Therefore, with the parts in position shown in Fig. 2, oil will flow from the chamber within the casing 8 into the chamber 4 because, by means of the tube 46 pressure in 100 105 110 115 120 125 130

the two chambers is equalized and the oil may flow downward by gravity. Any reduced pressure produced in the chamber 4 by the opening of the tube 46 and aperture 13 will not draw oil through the discharge line 44, which is connected to the crank case by means of a line 47, because of the ball check 48. This ball check is in the bottom of the conduit 44 which is provided with a seat at the upper end for the ball and a pin 49 therebelow preventing the ball from falling downward into the discharge line. As the chamber in the casing 4 fills under this condition with oil from the chamber 8, the float 33 raises which, by means of the lever 34 and link 36 raises the lever 37 and when the outer end of the lever 37, to which the spring 40 is connected, has been raised to a point where the spring is above the pivot point of the levers 37 and 39, the spring will raise the lever 39 opening the valve 41 and closing the valve 45. At this same time the aperture 13 is closed by the flap valve 50 carried on the end of a pivoted lever 90 and adapted to seat against the opening 13 by upward movement of the lever 37 on which the flap valve rests. In this position of the parts, the oil in chamber 4 may flow by gravity through the line 44 and 47 into the crank case and the chamber in the shell 8 and the chamber 14 are submitted to reduced pressure of the intake manifold. The structure described by reason of the chamber 7 being open to the exhaust manifold heats the oil in the chambers 14 and 8 and vaporizes the volatile constituents that may be therein which are drawn to the intake manifold and the refined lubricating oil is returned to the crank case.

Preferably this refiner device is used to take the oil from the space between the piston and wall of the cylinder in which it operates. This arrangement is shown particularly in Fig. 1, the line (which is the intake line for the refiner) opens directly through the cylinder wall as shown and the piston 51 is provided with a skirt 52 on one side which covers the port in the position of the parts shown in Fig. 1. This piston is provided with grooves 53 for the usual piston rings at the top and bottom and is also provided with a circumferential oil groove 54 and a longitudinal groove 55. When the piston moves downward from the position shown in Fig. 1 this groove 55 comes opposite the opening of the line 20 and oil in the grooves 54 and 55 is withdrawn under the reduced pressure in the oil refiner heretofore described and is there refined. This removal of the oil from the grooves removes any gasoline or hydro-carbon fuel that has passed downward from the combustion chamber between the piston and cylinder wall, and I have preferably arranged the mechanism to supply oil to the grooves on the compression stroke of the piston. This is one of the particular features of this invention. It is on the compression stroke that fuel oil is apt to be discharged down between the piston and cylinder wall and, by providing the means for supplying lubricating oil to the piston at this period, the oil not only assists in sealing the piston but also with the groove full of oil the fuel oil tending to pass downward by the piston is mixed with the lubricating oil and prevented from passing into the crank case. To supply the lubricating oil to the piston I provide a pump 56 which may be of any approved type (preferably gear type) which is located in a sump 57 provided in the crank case. This sump is provided by merely partitioning a part of the crank case from the balance thereof by means of a wall 57^a so that the oil supplied to the piston is always taken from this sump. This pump may be operated by a vertical shaft 58 actuated by a worm 59 from a similar worm on the cam shaft 60 of the engine. Rotation of the shaft 58 rotates the gears of the pump which takes oil from the sump and discharges it through a line 61 to a distributor 62 and from the distributor by means of a pipe 63 through the wall of the cylinder at 64. The oil groove 54, when the piston is in its lowermost position, is in alignment with the aperture 64 and the distributor at this instance has opened the line 63 to a flow of oil which floods the grooves 54 and 55. The distributor is utilized to intermittently furnish oil to the grooves and consists, as shown in Fig. 6, of an apertured plate 65 in a casing 66. The plate is on the rotating pump shaft 58 and the lower side of the casing is open to the line 61 and is also recessed as shown at 67 to which the aperture 68 of the plate is continually open. In the case of a single cylinder engine only one outlet pipe 63 is provided for the distributor so that once during each revolution of the distributor plate 65, the line 63 is opened to the supply line 61. It is to be noted that the shaft 58 is geared to rotate at one-half crank shaft speed for a four-cycle type of single cylinder engine and this is timed to bring the lines 61 and 63 into communication at the beginning of the compression stroke. With the two-cycle type of engine the speed of the distributor would be more rapid, a feature of the device being to discharge oil to the piston grooves on each compression stroke in any type of engine in which this device is adapted to be utilized. With a multiple cylinder engine additional lines for instance as indicated at 69, 70, 70^a in Fig. 8 and similar to the line 63 are provided so that the several lines are placed in communication with the oil supply line 61 in the desired succession so that on each compression stroke of each pis-

ton it is provided with a supply of oil. It is thus to be seen that this device is automatic in operation preventing dilution of the lubricating oil in the crank case by the continued removal of both the fuel and lubricated oil from between the piston and cylinder. It is also to be noted that the oil groove 54 and 55 are below the upper rings of the piston preventing the line 20 from having free opening to the combustion chamber of the cylinder.

A further desired feature of this invention is involved in the means for discharging cooled oil to the piston grooves. This is accomplished by inserting a cooler 95 in the discharge line 47 for the refiner. This may be of any approved type and is here shown as a series of tubes extending between the two heads 71 and 72, which tubes are provided with fins to radiate the heat of the oil passing therethrough. From the cooler the oil is discharged by means of the line 47 into the sump as shown in Fig. 1. This sump being a separate chamber from the crank case proper and the oil pump 56 being located in the sump, cooled oil is discharged to the piston and assists in reducing the temperature of the cylinder and piston. In order that the sump may never have all the oil discharged therefrom, I have provided an aperture indicated by the dotted lines 73 in Fig. 1 in the wall 57 between the sump and crank case proper. This is normally covered by a valve plate 74 carried on the end of the lever 75 pivotally supported on the wall 76 of the sump. This lever is provided with a float 77 which closes the aperture 73 when raised to a certain level separating the sump from the remainder of the crank case. As the engine operates and begins to use up the oil in the sump the oil level falls allowing the float to fall and open the aperture 73 which permits oil from the crank case to flow into the sump. This is merely a precautionary device to insure oil being in the sump at all times and keep the pump immersed. Normally the port 73 is closed.

The piston 51, as heretofore stated, is provided with a skirt 52 depending from the lower edge thereof on the side of the cylinder through which the pipe line 20 opens and this skirt prevents the opening of the pipe line 20 to the interior of the cylinder and crank case. In the instance of use of this device here shown there is no means provided on the piston for closing the aperture of the oil line 63 in the wall of the cylinder for the reason that a distributor device is provided which is necessary if oil is to be provided at stated intervals to the piston and is preferably used for such purpose and for use in conjunction with multi-cylinder engines. In the event of desiring to dispense with the distributor device a

skirt could be provided on the piston similar to the skirt 52 closing the aperture 64 of the line 63 to the cylinder when the piston is on its up stroke.

It is further found desirable to provide some means of preventing an overheating of the refiner device by the exhaust gases and for this purpose I have provided a thermostatically controlled valve indicated at 80 in Fig. 5 adjacent the intake for the exhaust gases into the chamber 7. This valve device is attached to a bimetallic element 81 of curved form extending for a distance around the wall of the case 6 and held in place by a lug 82 at one end and a similar lug 83 at the other end. On an excess of heat passing through the channel 9 for the exhaust gases the bimetallic element 81 will expand moving the valve 80 more or less closely against the inlet aperture for the exhaust gases and restricting the volume of flow of exhaust gases thru the chamber. The gases pass out of the chamber through an aperture 84 provided on the side of the chamber 7 opposite the inlet aperture. 90

It is also to be noted that the screen 15 is of value in maintaining the lubricating oil in a substantially pure state inasmuch as it serves to filter out all free carbon and other solids that may find their way into the oil channel of the piston. The oil is therefore upon removal first filtered, then refined by a heat treatment, then cooled, and finally returned to the crank case or sump for the pump. 100

Having thus fully described my invention, what I claim and desire to secure by Letters Patent of the United States is—

1. A lubricating device for a multiple cylinder type of internal combustion engine comprising in combination with the several pistons thereof each provided with oil retaining channels in the surface open to the respective cylinder wall, of a conduit opening through the wall of each cylinder, a source of oil supply, a distributor device adapted to connect the supply with each of said conduits in succession, said distributor device being timed to discharge oil into each conduit on the compression stroke of the piston in the respective cylinder, a suction means including a conduit in communication with an aperture in each cylinder wall with which the oil channel of the respective piston registers during the piston movement, a chamber into which the oil withdrawn by said suction means is discharged, means for heating the chamber to vaporize the volatile oils, and means in the chamber for discharging the oil when refined to the said supply source. 110

2. The combination with a cylinder, piston, and crank case, of an internal combustion engine, a division wall in said crank case providing a separate chamber, said wall 120

having an aperture, a float device in the chamber adapted to close the aperture when the oil is at a certain level, a pump in the said chamber, a conduit leading from the pump and discharging through the cylinder wall, the piston having an oil receiving groove or channel, an oil refining device subjected to the reduced pressure of the intake manifold of the engine, a conduit leading from the refiner device to and opening through the cylinder wall, said reduced pres-

sure of the refiner removing the oil from the groove when in registration with the said aperture, means for heating the refiner by the exhaust gases of the engine to vaporize 15 the volatile oils, and means for discharging the refined lubricating oil from the refiner to the said chamber in the crank case.

In testimony whereof, I sign this specification.

RICHARD C. ALAND.
